UNITED STATES PATENT OFFICE.

SAMUEL DORAIS, OF CHICAGO, ILLINOIS, ASSIGNOR TO EVANS, ALMIRALL & COMPANY, TRUSTEE, OF NEW YORK, N. Y.

FIRE-EXTINGUISHER.

1,042,536.

Specification of Letters Patent.

Patented Oct. 29, 1912.

Application filed May 27, 1909. Serial No. 498,696.

To all whom it may concern:

Be it known that I, SAMUEL DORAIS, a citizen of the United States, and a resident of Chicago, in the county of Cook and State 5 of Illinois, have invented certain new and useful Improvements in Fire-Extinguishers, of which the following is a specification.

This invention relates to fire extinguishers and relates particularly to sprinkler 10 heads for automatic sprinklers.

The object of the invention is to provide an improved sprinkler head for automatic sprinklers which will be simple, strong and durable in construction and reliable and 15 effective in operation.

A sprinkler head embodying my invention comprises the various features and details of construction hereinafter described and claimed.

20 In the accompanying drawing, in which my invention is fully illustrated—Figure 1 is a perspective view of a sprinkler head embodying my invention. Fig. 2 is a sectional elevation thereof taken substantially 25 on the line 2—2 of Fig. 3. Fig. 3 is a sectional, plan view thereof taken substantially on the line 3—3 of Fig. 2; and Fig. 4 is a perspective view of the members of the fusible strut separated.

30 My invention relates particularly to closures for sprinkler heads, the frame portions of which may be of any desired or approved construction.

As shown, the frame portion of my improved sprinkler head, designated as a whole by A, comprises a hollow bushing 1 which is provided with a screw thread on its outside adapted for engagement with a corresponding screw thread formed in a union on the 0 water pipe, not shown, whereby the head A may be secured to the water pipe with the hole 2 therethrough in open communication with the interior of said pipe. Formed on said bushing 1, are arms 3 supported at the ends of which is a boss 4 formed in which, in substantial alinement with the hole or opening 2 in the bushing 1, is a screw threaded opening adapted for engagement by a screw 5 adapted for exerting a desired pressure upon the closure for the hole or opening 2 in the bushing 1, as presently described.

The hole or opening 2 in the bushing 1 is

adapted to be closed by a cap 6 secured over the ends thereof. Said cap 6 may be of any usual or approved construction, being preferably stamped from a suitable piece of sheet copper or the like. A raised seat 7 is preferably formed on the bushing 1 around the opening 2 therein on which the cap 6 rests, said raised seat being preferably ground to a true surface to insure a tight fit of said cap 6 thereon, all in a familiar manner. To prevent accidental displacement of the cap 6, said cap preferably comprises a central depressed portion adapted to fit loosely inside of the raised seat 7.

The cap 6 is adapted to be secured in position upon the bearing 7 by means of what may be conveniently referred to as a toggle lever designated, as a whole, by 8, comprising substantially similar toggle members 9 and 10 which are adapted to be connected end to end and to be inserted between the cap 6 and the end of the screw 5, the outer ends of said toggle members 9 and 10 preferably terminating in rounded points and said cap 6 and screw 5 being provided with correspondingly rounded recesses or depressions 11 and 12, respectively, adapted to receive the pointed ends of said toggle members and which will operate to hold said toggle members in position thereon.

Formed on and projecting laterally from the toggle members 9 and 10, respectively, preferably adjacent to the connected ends thereof, are lever arms 13 and 14, the relation being such that, when the toggle members are inserted in flexed position between the cap 6 and screw 5, the outer ends of said lever arms 13 and 14 will be separated by a considerable space, a desirable space in practice being about $\frac{3}{4}$ of an inch.

A fusible strut, designated as a whole by 15, is adapted to be inserted between the ends of the lever arms 13 and 14 for the purpose of securing the toggle lever members 9 and 10 in position between the cap 6 and screw 5, in the manner heretofore described. As shown, said fusible strut 15 comprises three separate members 16, 17 and 18. The 100 strut members 16 and 17 are made from strips of metal, preferably brass, of proper width and thickness to afford requisite strength, say $5/16$ of an inch wide by $1/16$

of an inch thick, and are adapted to be soldered together in overlapped position by means of suitable soft solder fusible at a low temperature, say 160 degrees. The overlapping sides of said strut members 16 and 17 are relatively thin as compared with their ends, say about 1/2 the thickness thereof, the relation being such that when said strut members are secured together the outer surfaces thereof will be substantially flush with each other and the end of the strut member 16 will bear against a shoulder 19 on the strut member 17 between the relatively thick and thin portions thereof. Formed at the overlapping end of the strut member 17 is a hook 20 which is relatively narrow as compared with the width of said strut considered as a whole and which is adapted to extend through a corresponding hole or opening 21 formed in the strut member 16, said hole or opening 21 being longer than said hook 20 so that the ends thereof will clear said hook in both directions lengthwise of said strut, thus insuring that said hook will not catch upon the ends of said opening when said strut members 16 and 17 turn relatively to each other about the shoulder 19. The strut member 18 forms a key adapted for normally locking the strut members 16 and 17 together. Said strut member or key 18 is made of relatively thin sheet metal, preferably brass, and is soldered to the outer surface of the strut members 16 and 17. Formed on one end of said key 18 is a lip 22 which is adapted to interlock with the hook 20 which projects through the hole or opening 21; said lip 22 being preferably slightly narrower than said hole or opening 21, permitting said lip to enter said hole or opening 21 and providing for limited movement of the end of said lip with the hook 20 to effect disengagement of said hook from the hole or opening 21. Preferably, also, said key 18 is made of such length that it will overlap the shoulder 19 on the strut member 17, thereby providing for solder connection of said key to both of said strut members. The strut members 16, 17 and 18 are preferably correspondingly bent or bowed, whereby, when secured together to form the strut 15, said strut will be similarly bent or bowed. Said strut 15 is adapted to be inserted between the ends of the lever arms 13 and 14 with its concaved side disposed outwardly toward the ends of said lever arms and to prevent accidental disengagement of said strut from said lever arms, said lever arms are preferably provided adjacent to their outer ends with notches 23 and 24 adapted to receive the ends of said strut. If desired, my invention contemplates forming lugs 25 at the ends of said strut adapted to embrace the lateral sides 65 of the lever arms 13 and 14, which will

operate, in an obvious manner, to maintain said strut in desired lateral adjustment between the ends of said lever arms. Preferably, also, the lever arms 13 and 14 are made of different operative lengths, the arm 13 adapted for engagement by the end of the strut member 17 being preferably longer than the operative length of the strut member 16. 70

As shown, the toggle members 9 and 10 are entirely detached from each other and are held in engagement with each other, end to end, by the strut 15 inserted between the lever arms 13 and 14, a shoulder 26 on one thereof operating to support said toggle members from accidental displacement and also to define their designed positions relatively to each other. 75

With the described construction, it is obvious that when the closure has been assembled with the toggle arms 9 and 10 connected end to end in flexed position with the outer ends thereof in engagement with the recesses 11 and 12 in the cap 6 and screw 5 and with the fusible strut 15 inserted between the ends of the lever arms 13 and 14, setting up the screw 5 will tend to flex the toggle members 9 and 10, which will operate through the lever arms 13 and 14 to bring the strut 15 under compression so that, 80 when said strut 15 is subjected to a proper degree of heat, ordinarily 160 degrees, the compression stress thereon will operate to collapse said strut, allowing the lever arms to come together, thus flexing the toggle 85 members 9 and 10 and relieving the cap 6 from all pressure, which will thereupon be forced off from its seat by the pressure in the water pipe, permitting the discharge of water through the hole or opening 2 in the 90 head A. 95

With the described construction of strut 15, it is likewise obvious that, in collapsing under the pressure to which it is subjected in use, when the solder connecting the strut members becomes weakened by the application of heat, the end of the strut member 16 acting on the shoulder 19 of the strut member 17, will cause said strut members to swing inwardly about their points of connection to the lever arms 13 and 14, thus effecting disengagement of the hook 20 at the end of the strut member 17 from the hole or opening 21 in the strut member 16 and, through the action of the hook 20 on 100 the lip 22 at the end of the key or strut member 18, to break the solder joint connecting said key to the faces of the strut members 17 and 18. 105

Operating in the manner described, it is 110 obvious that there can be no turning of the strut members relatively to each other until the joints between all thereof have been broken and said toggle members are free to 115 collapse or fall apart when they have turned 120

125

sufficiently to effect disengagement of the end of the strut member 16 from the shoulder 19.

It will be observed that my construction is such that the device will have the maximum of stability and strength and yet the highest degree of sensitiveness. By having the arms 13 and 14 project in a direction opposite the direction in which the toggle 5 normally tends to break, I am not only enabled to locate the fusible strut at a considerable distance from the water-pipe and thus remove it from temperature influences of the water but am also enabled to employ a strut 10 of the buckling or collapsible type which is always advantageous in view of its stability and reliability as well as sensitiveness but which is especially advantageous when mounted as in my device between a pair of 15 arms projecting from a true toggle lever, since in that position the strut may be locked with a minimum of solder and thus while having ample stability in normal temperatures will have the utmost sensitiveness under high temperatures, it being obvious that 20 the ideal sprinkler-head must be one which will have under normal temperatures the maximum of stability and reliability of action and yet under a predetermined temperature shall act quickly and with positive certainty. And by having the operative length of one of the arms longer than the other the arms are caused to exert a 25 greater buckling or collapsing strain on the strut, thus enabling me to employ a strut having the least amount of offset or curvature, this minimum of offset being advantageous in that it contributes to stability by preventing accidental collapsing in temperatures below that at which the device is set 30 to operate. It will therefore be observed that in my device I employ the least possible amount of solder and thus obtain the highest degree of sensitiveness of operation 35 and yet so locate and arrange the parts that the necessary stability under normal temperatures is obtained.

I claim:

1. A closure for a sprinkler head of the type described, comprising a suitable cap adapted for closing the discharge opening in said head, toggle members adapted to be inserted end for end and in flexed position between said cap and a rigid part of said head, lever arms on said toggle members and a strut adapted to be inserted between said lever arms, the relation being such that said strut will be subjected to compression, the points of engagement of said strut with 50 said lever arms, respectively, being at different distances from the pivot of said toggle members, said strut comprising overlapping strut members soldered together, the overlapping end of one of said strut members bearing against a shoulder on the other strut member, the radial distance of said shoulder from the pivot of said toggle members being intermediate the radial distances of the points of engagement of the ends of said strut with the lever arms on said toggle members, respectively, from the pivot of said toggle members, substantially as described.

other strut member, the radial distance of said shoulder from the pivot of said toggle members being intermediate the radial distances of the points of engagement of the ends of said strut with the lever arms on said toggle members, respectively, from the pivot of said toggle members, substantially as described.

2. A closure for a sprinkler head of the type described, comprising a cap adapted for closing the discharge opening in said head, toggle members adapted to be inserted end for end in flexed position between said cap and a rigid part of said head, lever arms on said toggle members, a bent or bowed strut 70 adapted to be inserted between said lever arms, the relation being such that said strut will be subjected to compression, the points of engagement of said strut with said lever arms, respectively, being at different distances from the pivot of said toggle members, said strut comprising overlapping strut members soldered together, the overlapping end of one of said strut members bearing against a shoulder on the other strut member, the radial distance of said shoulder from the pivot of said toggle members being intermediate the radial distances of the points of engagement of the opposite ends of said strut with the lever arms on said toggle members, respectively, from the pivot of said toggle members, substantially as described.

3. A closure for a sprinkler head of the type described, comprising a suitable cap 100 adapted for closing the discharge hole or opening in said head, toggle members adapted to be inserted end for end and in flexed position between said cap and a rigid part of said head, lever arms on said toggle members and a strut adapted to be inserted between said lever arms, the points of engagement of said strut with said lever arms being at different distances from said toggle members, said strut comprising overlapping 105 strut members soldered together, the overlapping end of one of said strut members bearing against a shoulder on the other strut member, said shoulder being disposed between the points of engagement of the ends 110 of said strut with said lever arms, substantially as described.

4. A closure for a sprinkler head of the type described, comprising a suitable cap adapted for closing the discharge hole or 120 opening in said head, toggle members adapted to be inserted end for end in flexed position between said cap and a rigid part of the head, lever arms on said toggle members projecting therefrom in a direction opposite to the direction of flexure of the toggle members and a bent or bowed strut adapted to be inserted between said lever arms, the points of engagement of the ends 125 of said strut with said lever arms, respec- 130

tively, being at different distances from said
toggle members, said strut comprising over-
lapping strut members soldered together, the
overlapping end of one of said strut mem-
bers bearing against a shoulder on the other
strut member, substantially as described.

In testimony, that I claim the foregoing

as my invention, I affix my signature in pres-
ence of two subscribing witnesses, this 7th
day of May, A. D. 1909.

SAMUEL DORAIS.
